COMPASS

Joseph Meilner, West Orange, N. J., assignor to
Eagle Pencil Company, New York, N. Y., a cor-
poration of Delaware

Application January 29, 1936, Serial No. 61,266

7 Claims. (Cl. 33—149)

My present invention relates particularly to drafting compasses although certain of the general features thereof are applicable to dividers and certain particular features are applicable to marking implements more generally.

An object of the invention is to provide a practical low-cost drafting compass of durable construction made of a minimum number of metal stampings that are readily assembled and which admits of ready and dependable setting to the desired radius.

Another object is to provide an implement of the above type which affords simple and convenient means for adjusting and gripping the writing lead point at the marking arm.

In the accompanying drawing, in which is shown one of various possible embodiments of the several features of the invention,

Fig. 1 is a plan view of the drafting compass,
0 Fig. 2 is a transverse sectional view on a larger scale on line 2—2 of Fig. 1,

Fig. 3 is a view in longitudinal cross-section on an enlarged scale on line 3—3 of Fig. 1,

Fig. 4 is a fragmentary detail perspective view 5 showing the mounting of the arcuate scale arm,

Fig. 5 is a perspective view of the handle member,

Fig. 6 is a view in longitudinal cross-section taken on the line 6—6 of Fig. 3,

0 Fig. 7 is a detail transverse sectional view taken on line 7—7 of Fig. 3 and on a greatly enlarged scale,

Fig. 8 is a transverse sectional view taken on line 8—8 of Fig. 1,

5 Fig. 9 is a transverse sectional view taken on line 9—9 of Fig. 3, and

Fig. 10 is a view in longitudinal cross section of an alternative embodiment of lead holder.

Referring now to the drawing, the drafting compass includes two leg elements 10 and 11 connected together by a pivot rivet 12 and with an intervening handle member H having a web 13 sandwiched between the enlarged upper pivot wings 14 of the leg members.

5 The leg members are preferably of identical sheet metal stampings, each stamping being longitudinally folded or doubled over to afford two relatively wide identical flanks 15 and 16 with a narrow exterior longitudinal connecting body 17, affording a relatively narrow but deep channel conformation. Thus by virtue of its channel section the leg though of sheet metal, has adequate stiffness.

The pivot wing 14 of the sheet metal leg 10 projects as an integral extension in the plane

of the flank 15 as shown. The lower edge of the pivot wing 14 is curved at 19 on an arc struck about the pivot aperture 18 therein and the upper edge of the inturned or offset leg flank 16 is similarly curved at 20 about an arc struck from 5 the pivot center 18.

Preferably each leg has a pivot stud 21 extending inward therefrom laterally of the pivot hole, and illustratively to the left thereof, and at the inner face of the pivot wing. The stud 21 10 may be in the form of a pin affixed in the wing, but is preferably an instruck dent or embossment as shown.

The web 13 on the handle member H has two apertures 22¹ and 22² into which the respective 15 studs 21 extend when the said web is sandwiched between the two wings of the leg members, and said web also has a short elongated longitudinal slot 23 therein to accommodate the pivoting connection rivet member 12. Preferably, the rivet 20 20 12 has a spring washer 24 under one head thereof to exert yielding pressure for maintaining the parts against inadvertent shifting from any set position. It is clear from the assembly described that in any and all settings thereof, the handle 25 will extend symmetrically to bisect the exterior angle between the two legs, and the pivoting rivet 12 occupies a higher or a lower position along the elongated slot 23 depending on whether the compass is set for a smaller or a larger radius.

The arcuate scale arm 26, struck as usual about the pivot 12 as a center, is preferably located at one end thereof within the deep channel of leg 10, a short and narrow integral tang 27 from 35 one end of the scale arm projecting through a corresponding small aperture 28 in the body of the leg 10 being turned over so that the inner end 26¹ of the arm 26 snugly fits against the body 40 of the leg 10 or floor of its channel conformation.

The opposite or free end of the scale arm extends across the depth of the channel of the other leg 11 and protrudes outward therefrom through a corresponding slot 30 in the body thereof. The scale arm is of thickness equal to 45 the width of the channels of the legs, so as to snugly occupy the space therebetween. The snug engagement of the scale arm in the channel conformation of leg 11 accordingly assists in frictionally retaining the compass in any position 50 of adjustment. Moreover, the scale arm serves to maintain the two legs with the forward flanks of the respective legs in a common plane and the rear flanks in a common plane adjacent said first plane, and thereby affords the proper space be- 55

tween the pivot wings 14 to accommodate therebetween the web 13 of the handle member, which web is preferably of corresponding thickness.

- 5 The lower ends of the respective legs are preferably narrow and rounded to form sockets 31 which are longitudinally split at 32 in alignment with the channel opening. These sockets serve firmly to grip and retain the respective divider or compass points. Illustratively the metal stylus 33, is frictionally gripped at its rear end by socket 31 on the leg 11 and, of course, it may also be brazed or soldered in place and for dividers a similar stylus would be similarly disposed in the other leg 10.
- 10 15 In the compass construction set forth, a writing or pencil point is preferably held by the other leg 10. For this purpose, it is preferred to dispose in the socket 31, in lieu of the stylus at the right, a lead holding tube 35, which is preferably longitudinally slotted at 36 in registry or alignment with the slot 32 of the socket 31. Lodged in the lead holder tube is a lead positioning wire 37, the forward end of which abuts the short length of lead 38 positioned in the forward end of the lead tube. For ready manipulation, the positioning wire has an end 39 turned outward through the slot 36 of the lead holder tube, and when near its uppermost position also through the corresponding slot 32 in the socket 31, said projecting end serving for ready manipulation of the wire. Preferably, the extremity of said wire is coiled around completely to encircle the socket 31 in one convolution 40, thereby to afford a ring readily held between the thumb and forefinger for advancing or retracting the follower wire.
- 20 25 30 35

For locking the length of lead in set position, the forward tapered end of the lead tube is longitudinally slit at 41 for resilience and a length of said tube in advance of the slot 36, is threaded at 42 for accommodating a removable clutch sleeve 43 the reduced end 44 of which grips the split extremity of the lead tube and causes it firmly to grip the lead 38 in fixed position. By the means set forth, it is apparent that as the lead is consumed, it is merely necessary slightly to loosen the clutch sleeve 43, to push the ring 40 of the positioning wire 37 downward to advance the lead, so that the effective length of the lead carrying leg becomes equal to that of the stylus carrying leg and thereupon to retighten the clutch sleeve to lock the lead into set position.

In order to avoid any possibility of the setting ring 40 being arrested by the extremity of the sleeve 43 whenever it is pushed back from around the protruding length of the lead holding tube 35, said extremity is rounded at 44.

In the alternative and preferred embodiment of Fig. 10 corresponding parts are designated by the same reference numerals primed. The lead positioning wire 37' extends in the unslotted lead holding tube 35' and longitudinally thereabove within the channel formation of the leg 10'. In this embodiment the wire 37' has an end 39' turned outward in this case through a longitudinal slot 36' along and symmetrically of the leg channel construction, the outer end of the wire being headed at 40' in the manner of a pin head exposed at the exterior of the arm and by manipulation of which, preferably with the thumb or the thumb nail the positioning wire 37' may be adjusted along the slot 36' for positioning the lead in substantially the same manner as in the other embodiment previously described.

75 Preferably the slot 36' is of width such as snug-

ly to accommodate the diameter of the wire end 39' to prevent looseness of the wire in use of the compass.

The combined web and handle structure is preferably made of two superposed wings welded or brazed together at 45 each with an integral stem extension 46 longitudinally thereof and of a longitudinal channel form. A sheet metal tube 47 is lodged between said stem elements and firmly gripped or welded in place, as a unitary structure therewith. The space within tube 47 may be utilized as a reservoir for extra leads. A handle sleeve member 48 which may be of enameled metal and is closed at its upper end is preferably telescoped over the stem assembly 46-47, and frictionally gripped thereby. Said handle sleeve member 48 is preferably hexagonal or octagonal in cross-section so that its sides will frictionally grip the longitudinal edges 49 of the respective stems 46 for secure assembly thereon.

It will thus be seen that there is herein described apparatus in which the several features of this invention are embodied, and which apparatus in use attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

Having thus described my invention, what I claim as new and desire to secure by Letters Patent of the United States is:

1. In a writing implement, a lead holder tube having lead gripping means at its forward end and a slot along its length, a pusher wire in said slotted portion, said wire having its rear extremity protruding through said slot and coiled around the lead holder for convenience of manipulation thereof, in adjustment of the position of said lead.

2. In a drafting compass a leg having a socket at its lower extremity, split to provide a longitudinally extending slot, a longitudinally slotted lead holder tube affixed in said socket with the slots of the tube and socket in registering position, a lead pusher wire in said lead holder tube, the rear end of said wire protruding outward through said slots for convenient manipulation thereof, the forward end of said lead tube being slit and clutch means for tightening the lead near its protruding end in writing position.

3. In a drafting compass a sheet metal leg longitudinally doubled in channel formation and presenting a socket at its forward end, longitudinally split to provide a slot, the forward edge of said socket being rounded, a longitudinally slotted lead holder tube affixed in said socket with its slot substantially registering with that of said socket, the rear end of said lead tube being slotted and a portion of the length of said tube in advance of said slotted portion being threaded for accommodating a clutch sleeve to lock the lead in adjusted position, the rear end of the pusher wire protruding through said slots and coiled around said socket for convenient manipulation thereof, the forward end of said socket being rounded for ready riding of said coiled portion in the course of adjustment, from the protruding length of said lead holder tube over the length of said socket.

4. In apparatus of the character described, a handle unit comprising a flat web structure having flattened elongated stems protruding from the face thereof said stems presenting channels facing but spaced from each other, an insert snugly fitted and securely retained between said channels, and a sleeve telescoped over and frictionally engaging the outer or convex surfaces of said stems.
- 10 5. A compass lead comprising a channel-shaped leg having side flanks and a socket at its lower end, a lead holder tube affixed in said socket having lead clutching means at the forward end thereof, a lead pusher wire extending at its lower end into said socket and having a portion of the length thereof longitudinally within the channel formation of said leg, said wire having an

out-turned head, the end protruding through a longitudinal slot in said leg for adjusting the position of said wire and also of said lead.

6. The combination recited in claim 5 in which the longitudinal slot is symmetrically between the flanks of the channel construction and is of width corresponding to the diameter of the pusher wire for frictional hold thereon.

7. In an apparatus of the character described, a handle unit comprising a flat web structure 10 having a pair of flattened elongated stems protruding from one end thereof, and presenting channels facing each other, and a sleeve telescoped over and frictionally engaging the outer or convex surfaces of said stems, and forming 15 with said stems a magazine for compass leads.

JOSEPH MEILNER.
